UNITED STATES PATENT OFFICE.

WILLIAM L. MILLS, OF WHITMAN, MASSACHUSETTS, ASSIGNOR TO IMPROVED SHOE METHODS CORPORATION, OF PORTLAND, MAINE, A CORPORATION OF MAINE.

WELT SHOE.

Application filed September 22, 1927. Serial No. 221,231.

The present invention relates to the manufacture of boots and shoes, and more particularly to that type of shoe in which the out-seam stitches, which secure the outsole to the shoe, are anchored in a welt located outside the shoe, and the inseam stitches which secure the upper to the insole are buried within the insole out of contact with the wearer's foot. At the present time the standard shoe of this type is the Goodyear welt.

There is an inherent defect in the Goodyear welt shoe. In order to secure the upper, welt and insole together by means of the inseam stitches, it is necessary to provide the insole with a sewing rib to which the upper and welt may be attached. If now an outsole is placed over the ribbed insole it will rest on the rib and a hollow space is formed between the two soles. In order to fill this hollow space a layer of plastic material is spread on the insole inside the rib so that when the outsole is fastened to the welt it rests on a substantially level shoe bottom. With this construction when the finished shoe is new the inside surface of the shoe is perfectly smooth. In use, however, the heat of the foot softens the underlying plastic material and in walking this becomes displaced so much that if any shoe of this type is examined after being worn a short time the inside surface will be found to have become humped and hollowed to the general shape of the foot. This alteration of the original form of the inside of a Goodyear welt shoe results in the foot being clamped as in a vise so that all the elements provided by nature for the protection of the foot and/or for aiding in propelling the wearer forward, are prevented from performing their proper functions. According to the opinion of orthopedic surgeons the greater number, if not all, of the more common foot troubles may be attributed to this source.

Many attempts have been made to correct this inherent defect in a Goodyear welt shoe. Heretofore, it has been proposed to secure the upper and welt to an insole while the upper and welt were positioned entirely outside the peripheral edge of the insole thus to avoid the characteristic sewing rib in a Goodyear

welt insole. With this proposed construction the insole and outsole may be secured together in a face to face manner thus obviating the use of the troublesome insole filler. But a shoe so made exposed the full width of the welt to view and thus made the welt such a prominent feature of the shoe as to seriously detract from the appearance thereof and, furthermore, made the wearer and the observer of the shoe believe that the shoe was a stitch down or some other radical departure from standard welt shoe construction. I am aware that two attempts have been made to correct this unsightly defect in the construction of welt shoes of the type characterized by an absence of insole filling. In the first attempt the shoe was made on a special last so that on completion of the shoe the welt would be partially hidden beneath the upper. This shoe required newly created machines, special lasts and special appliances for its manufacture. In the second attempt the insole was provided with a feather in accordance with the requirements for a standard Goodyear welt insole but, before lasting, this feather was removed on each side of the insole from a point adjacent the tip line to a point in the shank adjacent where the forepart curvature on the periphery of the insole is reversed. When this insole was secured to the bottom of a last of its own size and original width the portions of the edges of the insole from which the feather had been removed were inset from the edge of the last, i. e. while the toe and shank fitted the last the main portion of the forepart was narrower than the last. With an insole constructed and positioned on the last as described it is possible to make a welt sole without a sole filler upon standard shoe machines. But shoes so made are defective because, with the narrowed insole, the foot of the wearer must tread on the crease between the edge of the insole and the upper along the portions of the insole from which the feather has been removed, resulting eventually in more discomfort and more serious injury to the feet than with the insole filled type of welt shoe.

The object of the present invention is to produce an attractive welt shoe, of the type

characterized by an absence of fugitive sole filling material, which may be manufactured on standard lasts and with standard shoe machines, and which is provided with an insole 5 having a comfortable and non-injurious foot supporting surface.

To the accomplishment of this object and such others as may hereinafter appear, the features of the present invention relate to certain combinations, constructions, arrangements of parts and methods of manufacture fully set forth hereinafter, the advantages of which will be readily apparent to those skilled in the art.

The various features of the present invention will be readily understood from an inspection of the accompanying drawings illustrating the best form of the invention at present known to me, in which:

Figure 1 is a plan of the insole positioned on the bottom of a last;

Fig. 2 is a plan of the step product of my method after the shoe has been lasted, welted, and vamp trimmed;

Fig. 3 is a sectional elevation on the line 3—3, Fig. 2;

Fig. 4 is a detail center-line sectional elevation of the toe of a finished shoe; and

Fig. 5 is a detail in sectional elevation of a completed shoe on a line corresponding to 5—5, Fig. 2.

In the illustrated embodiment of the invention an insole 6 is died out so that its edge will register with the edges of the last upon which the shoe is to be made. The insole 6 is then fitted with a channel 8 and three separate shouldered feathers 9, 10 and 11. The feather 9 extends around the toe of the insole 6 forward of the tip line. The feathers 10 and 11 are located upon opposite sides of the insole and preferably extend from a point adjacent the welt butt point 12 substantially to the point in the shank where the forepart curvature is reversed. The feathers 9, 10 and 11 may be formed during the channeling operation by any suitable type of knife that provides for a sewing shoulder and the portion of the insole having an unshouldered edge extending between these feathers covers the full 50 width of the last.

The channeled and partly shouldered insole is then secured to the last 7 so that the periphery of the insole lies flush with the periphery of the bottom of the last (Fig. 1). The upper 13, including the usual lining, counter and box, is assembled with the last and insole and is then lasted. At the toe and at the shank adjacent the welt butt points the upper is drawn, during the lasting operation, over the feathers and against the shoulders, however formed, in accordance with the usual method of lasting welt shoes. At the unshouldered edge faces of the insole which extend between the shoulders at the shank and toe and lie at the edge of the last, the upper is

overdrawn upon the flesh face of the insole so that the upper adjacent the unshouldered edge faces of the insole drum-heads over the exposed edge of the insole. The lasted shoe is then provided with a welt 14. As shown in Figs. 3, 4 and 5 the inseam stitches 15 are anchored in a groove 16 on the welt and in the bottom of the channel 8 and pass through the shoulder of the insole at the feathers 9, 10 and 11 and through the intact edge faces of the insole between the shank and toe feathers. During the inseam sewing operation the tension on the thread draws the upper tightly into contact with the intact edge faces of the insole at the unshouldered portions thereof (Fig. 3).

After the welt applying operation the stay tacks which hold the lasted upper in position for sewing the inseam are removed and the channel flap is cemented back into the channel 8 restoring the unbroken surface of the insole. The free edge of the upper 13 is trimmed flush with the adjacent face of the insole from the welt butt point 12 on the outside of the shoe to a point adjacent the ball line on the inside of the shoe (Fig. 2). The untrimmed portion 113 of the upper 13 is turned down upon and is cemented to the adjacent face of the insole. The portion 113 of the upper and its lining function to fill up the hollow at the inside of the shoe created by the shape of the instep portion of the last. A shank-piece may, if required by the type of last, be laid beside the inturned margin of the upper. An outsole 17, moulded if desired, is laid and leveled on the substantially level bottom formed as above described and the shoe is then subjected to the usual subsequent making and finishing operations for Goodyear welt shoes.

With this construction and method of manufacture no plastic material is required to fill a large cavity between the insole and outsole. The small cavities, formed between the insole and the outsole at the shank are adequately filled by the untrimmed portion of the inturned upper or a shank piece, or both, neither of which are displaceable like the usual insole filler. The shoulders at the toe and shank portions of the insole permit the upper to be lasted in snugly to the last at these portions of the shoe thus retaining the lines of the last in the completed shoe which gives style and perfection to the shoemaking. The welt, at the feathered toe and feathered shank forward the welt butts, is drawn under these feathers and under the inlasted upper thus making the shoe, in the external appearance of its shank and toe, the counterpart of a standard Goodyear welt shoe. Moreover, as the unshouldered or intact edge faces of the insole extending between the shank and toe shoulders lie at the edges of the bottom of the last, the forepart of the foot of the wearer is wholly and adequately supported by the insole well within the creases between the edges

of the insole and over-lasted upper. This construction provides a roomy and comfortable shoe and yet one that is snug where snugness is a requisite and without sacrificing either style or fine shoemaking standards. The outsole 17, by pressing upon the untrimmed and overlaid skirt 113 of the upper 13, relieves the inseam of much of the strain to which it would otherwise be subjected.

10 The nature and scope of the invention having been indicated and its preferred embodiment and method of manufacture having been specifically described, while yet recognizing that some modifications and changes may be 15 made without departing from its spirit and scope, what is claimed as new, is:—

1. That improvement in the art of preparing insoles for welt shoes which consists in cutting the insole to lie with its edge flush 20 with the edge of the bottom of the last upon which the welt shoe is to be made, and partially feathering said edge of the insole, namely, around the toe extending forward of the tip line and at the shank from sub- 25 substantially the welt butt points forward substantially to the points where the direction of the forepart curvature is reversed.

2. That improvement in the art of preparing insoles for welt shoes which consists 30 in cutting the insole to lie with its edge flush with the edge of the bottom of the last upon which the welt shoe is to be made, channeling the insole, and fitting said insole edge with disconnected shoulders along said chan- 35 nel at three separated places, namely, around the toe extending forward of the tip line and at the shank at each side thereof from a point adjacent the welt butt point to substantially the point where the direction of the fore- 40 part curvature is reversed.

3. That improvement in the art of making welt shoes which consists in preparing an insole by cutting to lie with its edge flush with the edge of the bottom of the last upon 45 which the welt shoe is to be made, by chan- neling the flesh side and by shouldering the insole edge at three separated places, namely, around the toe extending forward of the tip line and at the shank at each side thereof 50 from a point adjacent the welt butt point to substantially the point where the direction of the forepart curvature is reversed; as- sembling the insole on the last by register- 55 ing the edge of the insole with the edge of the bottom of the last; lasting the upper; securing a welt to the upper and insole; trimming the free edge of the upper flush with the adjacent face of the insole from substantially the welt butt point on the out- 60 side of the shoe to a point adjacent the tip line on the inside of the shoe; turning the untrimmed portion of the upper down upon the adjacent face of the insole; applying an outsole over the insole and turned down up- 65 per; and finishing the shoe.

4. In a welt shoe, an insole having a shoul- 70 der around the toe extending forward of the tip line, a shoulder on each side of the shank adjacent the welt butt points, and a forepart intermediate said shoulders of the full width of the last on which the shoe is built, having an unshouldered edge at each side of said forepart between said shank and toe shoul- 75 ders.

5. In a welt shoe, an insole having a mar- 80 ginal channel, a shoulder about the toe out- side of said channel, a shoulder on each side of the shank adjacent the welt butt points outside of said channel, and a fore- part intermediate said shoulders of the full width of the last on which the shoe is built, having an unshouldered edge at each side of said forepart between said shank and toe shoulders.

6. A welt shoe having the excess margin 85 of the upper turned down upon the adjacent face of the insole from a point adjacent the welt butt point on the inside of the shoe to a point adjacent the ball line on the inside 90 of the shoe, said margin being elsewhere in- seam trimmed.

7. A welt shoe having, in combination, an upper, an insole having a width in the re- 95 gion of the ball of the full width of the last bottom, a welt stitched to the upper and in- sole, said welt being drawn by said stitching partially beneath the upper and insole at the toe and at the shank adjacent the welt butt points but lying wholly outside the upper and the peripheral edge of the insole 100 at said ball portion thereof, and an outsole secured to the welt.

8. A welt shoe having, in combination, an upper, an insole having a width in the region of the ball of the full width of the last bot- 105 tom, an upper generally inseam trimmed but having a skirt from a point adjacent the welt butt point on the inside of the shoe to a point adjacent the ball on the same side of the shoe retained and overlaid on the insole 110 as a filler, a welt secured to the insole hav- ing its lower face in the plane of the lower face of the filled insole, and an outsole se- cured to the welt against said welt, filler and insole.
